ULTRA HIGH FREQUENCY TUBE

Richard S. Briggs, North Beverly, Mass., assignor
to Sylvania Electric Products Inc., Salem, Mass.,
a corporation of Massachusetts

Application September 18, 1945, Serial No. 617,035

2 Claims. (Cl. 315—5)

1

This invention relates to ultra high frequency tubes and in particular to tubes employing a resonant circuit of the cavity type.

Such tubes heretofore have been made with the metal parts of the cavity extending directly through and sealed to the glass walls of the tube, for example, as shown in the patent application Serial No. 490,703 filed on June 12, 1943, by H. J. McCarthy, and now U. S. Patent No. 2,413,364, granted December 31, 1946.

My invention provides a means of making tubes for resonant cavities without the necessity of sealing portions of the cavity through the glass walls of the tube.

I couple high frequency conducting elements inside the tube to those outside by capacitative coupling directly through the glass dielectric walls of the tube, by providing those elements with sufficient surface areas in register through said glass. Difficult ring seals between the metal of the high frequency elements and the glass of the tube are thus eliminated, with consequent increased mechanical strength of the tube and obviation of the difficulty of securing uniform and adequate contact to the conductors otherwise necessary to complete the cavity outside the tube. Although I have used the word "glass" in describing the invention, I have used it in a generic sense to include any dielectric material of which the tube may be made, such as quartz, ceramics or the like in addition to the more usual tube glasses.

A particular feature of the invention is a simplified oscillator tube using my construction, although my invention is applicable to any type of tube employing a cavity part of which is external to the tube, and is particularly applicable, for example, to the tube commonly known as the "lighthouse" tube, and to tubes such as shown in the previously mentioned McCarthy application.

Other objects, features and advantages of my invention will be apparent from the following specification taken in conjunction with the accompanying drawings.

Figure 1 shows a profile section of my invention; and

Figure 2 shows a plan view.

In Figure 1, the envelope 1 may be a bulb of glass, quartz, or the like, as previously noted. The lead-in wires 18 and 20 are connected to, and support, the cathode 4 which may be, for example, a nickel cylinder coated with one or more of the alkaline earth oxides or other material of low-work function. One end of the filament heater coil 5 is also connected to the lead-in

2

wire 18 and the other end of the cathode heater coil is connected to the lead-in wire 19. The lead-in wire 17 is attached to the small grid-lead choke coil 8 which in turn is connected to the grid cup 3 which surrounds the cathode and which has an annular opening covered by the grid 11 which may be of wire mesh. The cylindrical walls 23 of the grid cup 3 may have a flange 24 which may be connected to the mica spacer 16 by the insulating supports 14 to hold the two parts together. The lead-in wires 17, 18, 19 and 20 also pass through the mica spacer or disc 16 and may be attached thereto by the eyelets 26 if desired. The anode cup 2 is supported above the grid 11 and is spaced therefrom by the insulator rods or support 12. This anode cup comprises a flat circular end 21 close to the grid 11 but spaced therefrom, the cylindrical walls 28, the annular portion 29 and the cylindrical portion 30, all of which portions are in electrical connection and are preferably all in one piece. The top of the plate may have flanges or tabs 31 which may be connected to the mica spacer or disc 15 by the insulating supports 13. The plate 15 choke coil 9 may be connected from the circular flat part of the plate to the lead-in wire 7 which passes through the glass envelope 1 at the bead 31. Similar beads 32, 33, 34 and 35 surround the other lead-in wires 17, 18, 19 and 20. If desired, the usual stem press common in radio tubes may be used around these lead-in wires instead of the separate beads shown.

The elements so far described are all parts of the tube proper and form one integral unit. The metal toroid or cavity 6 is a separate unit external to the tube and is made of good high frequency conducting material such as copper, or silver, or may be merely plated with such a metal, if desired. In the lateral cross section as shown in Figure 1, the walls of the toroid do not completely close but have the flat portions 21 and 22 parallel to the glass of the tube and spaced apart from each other in order to form a resonant cavity in conjunction with the elements inside the tube. The portions 23 and 30 of the anode and grid cups are likewise flat and parallel to the glass walls of the tube and act with walls 21 and 22 of the cavity to form condensers which couple the external and internal parts of the cavity 6. The walls 21 and 22 of the cavity 6 outside the tube may bear directly on the glass envelope 1 of the tube, but it will be desirable to separate the walls 30 and 23 of the anode and grid cups from the tube wall 1 so that the anode and grid cups may be heated by high frequency induction during the

manufacture of the tube, to drive off any occluded gases. It will generally be desirable to place the walls 23 and 30 of the grid and anode cups as close to the walls as possible without the danger of cracking the walls of the glass when the anode and grid cups are heated during the exhausting of the tube. The tube will ordinarily require a high vacuum.

It is now clear that the cavity 6 will be capacitively coupled to the grid and anode cups and with them form one complete cavity of definite resonant frequency and that in the particular construction shown, the tube with its cavity will form an oscillator of the Hartley type, the cathode being connected to the external cavity at some convenient point which will allow oscillations.

The same type of capacitively coupled cavity construction may, of course, be used in other types of tubes as already explained, that described being merely by way of example and not by way of limitation. My capacitively coupled cavity is applicable to all types of tube otherwise using a resonant cavity extending conductively through the glass walls of the tube.

It is clear that the inner cylindrical walls 23 and 30 of the grid and anode cups 3 and 2 should be very close to the glass walls of the tube but spaced slightly therefrom in order to allow proper heating of the anode and grid cups 3 and 2 during the manufacture and exhaust of the tube. The cylindrical area of these anode cups must, of course, be large enough to provide the necessary coupling capacity, which will ordinarily not need to be very great at ultra high frequency. The elements in the tube, particularly the grid and anode cups must be very rigidly held and kept accurately in line with each other and should be arranged so that the spacing between them remains uniform over the normal range of tube operating temperatures.

The metal anode and grid cups 2 and 3 should be made of, or at least plated with, a material of good conductivity for ultra high frequencies.

The insulating spacers 12, 13 and 14 may best be in the form of short rods, spaced around the surface of the parts supported.

What I claim is:

1. Ultra-high frequency apparatus including a vacuum tube comprising: a sealed cylindrical di-

electric envelope; a cathode therein; a metal grid cup surrounding said cathode and having a central opening in register with said cathode; a grid over said central opening and in electrical connection with said grid cup, said grid cup having a cylindrical metal wall spaced from but close to and coaxial with said cylindrical envelope; a metal anode cup having a flat circular end close to said grid but spaced therefrom, a cylindrical portion extending from said flat circular end to an annular portion, and a cylindrical portion close to but spaced from said cylindrical envelope, all portions of said anode cup being in electrical connection with each other; and a toroidal metal cavity resonator coaxial with said envelope and having its inner wall cylindrical, with a cylindrical opening along the middle of said inner wall to divide the same into two opposite cylindrical walls close to but spaced from said cylindrical envelope, extending toward each other but having their edges spaced from each other, one of the cylindrical walls of said resonator being in register with the cylindrical metal wall of said grid cup and in capacitive relationship therewith and the other of said cylindrical walls of said resonator being in register with the cylindrical portion of said anode cup and in capacitive relationship therewith.

2. The combination of claim 1, and lead-in wires for said cathode, said grid cup and said anode cup extending through said envelope; a choke coil inside said envelope and connecting said anode cup to one of said lead-in wires; and another choke coil inside said envelope and connecting said grid cup to another of said lead-in wires.
